UNITED STATES PATENT OFFICE

HJALMER C. GUSTAFSON, OF DENVER, COLORADO, ASSIGNOR TO GARDNER-DENVER COMPANY, OF DENVER, COLORADO, A CORPORATION OF DELAWARE

FLUID-OPERATED TOOL

Application filed May 21, 1928. Serial No. 279,371.

The object of the present invention is to provide a novel means for controlling the operation of an automatic valve so as to stop it in a position to hold the piston stationary, 5 with air or other motive fluid supplied to the piston chamber for hole cleaning purposes, the controlling means being such that it can be actuated either by a pushing movement or a pulling operation, thus making the valve 10 adaptable for convenient use under different kinds of drilling operations.

In the accompanying drawings:

Figure 1 is a longitudinal sectional view of a portion of a drilling tool, showing the novel 15 controlling means in elevation.

Figure 2 is another view showing the controlling means in longitudinal section.

Figure 3 is a detail view of the controlling valve when shifted to a position to hold the 20 automatic valve.

Figures 4, 5 are cross sectional views respectively on the lines 4—4 and 5—5 of Figure 3.

Figure 6 is a top plan view of the controlling valve mechanism and showing a slightly modified form of structure.

Figure 7 is a sectional view on the line 7—7 of Figure 6.

Figure 8 is a longitudinal sectional view 30 diagrammatic in its character to show the various instrumentalities and indicate their manner of operation.

In the embodiment disclosed a cylinder member 9 is provided, which may be of any 35 well known character and said cylinder member has a piston chamber 10, in which reciprocates a piston body 11 having a hammer extension 12. This piston 11—12 is provided with a chamber 13 to receive the usual rifle 40 bar 14, and a passageway 15 leads from the front end of the chamber through the front end of the hammer extension 12, so that it constitutes a conduit for directing fluid from the rear portion of the piston chamber behind the piston through said piston, to the bore of a drill steel in a manner well understood.

In rear of the piston chamber 10 and fitting 50 into the rear end of the cylinder 9 is a valve casing 16 having an internal annular supply

groove 17, with which is connected a supply passageway 18 leading from any suitable source. In front of the supply groove 17 is a distributing groove 19 and in rear of said supply groove 17 is another distributing 55 groove 20. Behind the distributing groove 20 is an exhaust groove 21 having communication with atmosphere through the passageway, indicated at 22. Behind the exhaust groove 21 is a valve flange-receiving groove 23. The front distributing groove 19 is in communication with the rear end of the piston chamber through a series of ports 24 and the rear distributing groove 20 is in communication with the front end of the piston chamber by a passageway 25. The rear end of the flange-receiving groove 23 is in communication with the rear portion of the piston chamber by a trip passageway 26.

Located within the valve casing 16 and 70 spaced from the walls thereof is a plug 27 having a reduced front portion 28, providing an abutment shoulder 29. On said plug and within the casing is a reciprocatory distributing valve 30 having at its rear end a flange 75 31 operating in the flange-receiving groove 23. The front end of the valve 30 is movable to and from a position to cut off communication between the supply groove 17 and the front distributing groove 19, as will be clear 80 by a comparison of Figures 1 and 2. Said valve has an externally reduced central portion 32 that is movable to and from a position to afford communication between the supply groove 17 and the rear distributing 85 groove 20. This reduced portion furthermore is movable to and from a position to establish communication between the distributing groove 20 and the exhaust groove 21. The front end of the valve 30 slidably 90 fits the reduced portion 28 of the plug and thereby produces an internal pressure chamber 33, of which the shoulder 29 constitutes the rear wall and this chamber is in constant 95 communication with the supply groove 17 by ports 34 formed in the valve. The piston chamber 10 is normally open to atmosphere through an exhaust port 35 that opens through the side wall of the cylinder and is traversed by the piston head 11.

With the structure as thus far described, the normal operation is as follows: With the piston in its rear position, as shown in Figure 1, and with the distributing valve 30 in its rear position, motive fluid, such as air supplied through the passageway 18, will flow through the supply groove 17, and passing the front end of the distributing valve 30, enter the rear end of the piston chamber 10 through the ports 24, thereby driving the piston forwardly. The exhaust in advance of the piston takes place partly through the port 35 until said port is covered by the piston and thereafter it will flow through the passageway 25, the rear distributing groove 20, the reduced portion 32 of the valve 30, the exhaust groove 21 and the exhaust passageway 22. When the piston is thereby advanced sufficiently it will uncover the inlet end of the passageway 26 and the air under pressure will flow through said passageway and against the rear face of the flange 31 of the automatic distributing valve 30. Said valve will thereby be pushed forwardly or to the position shown in Figure 2. Now the supply of air to the rear end of the piston chamber 10 is cut off by the front end of the automatic valve, but at the same time the air distributing groove 20 is open to the supply groove 17 by the reduced portion 32 of the valve. Live air will consequently flow through the passageway 25 to the front end of the piston chamber, driving the piston rearwardly. Incidentally the air behind the piston will partly exhaust through the port 35, but it will also find its way through the passageway 26 and to atmosphere through the exhaust passageway 22, because there is a relief port 36 between said passageways 26 and 22. This relief port, however, is of less capacity than the passageway 26. When the piston crosses the mouth of the passageway 26 it will trap air behind it, thereby increasing the pressure until its power is sufficient to push back the valve 30 and this is readily accomplished because of the reduction in pressure behind the flange 31 due to the leakage of the air through said relief port 36.

Now it is an important feature of this invention to provide means for holding the piston 11-12 at the front end of its stroke with the extension 12 against the tool and with air under pressure flowing freely into the piston chamber 10 behind the piston body 11, so that a constant supply of air under pressure will pass through the piston by way of the chamber 13 and bore 15 to effect the cleansing of the drill hole. The following means is employed for effecting this very desirable result.

Formed upon one side of the cylinder member is an open-ended valve casing 37 having a front chamber 38 and a reduced rear bore 39, these two opening entirely through said casing 37. A reciprocatory

plunger valve 40 is located in the chamber 38 and has a rearwardly extending stem 41 in the chamber 39. A coiled spring 42, surrounding the stem and abutting against an internal flange 43 in the chamber, also abuts against a plunger head 44 fixed to the stem 41. This spring obviously holds the valve in its rearmost position and the plunger head 44 projecting from the rear end of the casing 37 constitutes a thumb piece by which the valve can be pushed forwardly. The valve has a longitudinally extending lip 45 on its front end that projects beyond the casing 37 and to which can be secured a cable 46 or other device extending to any convenient point and which can be pulled to shift the valve. By reference to Figures 2 and 8 it will be noted that the exhaust port 35 opens at the front end of the valve casing 37 and under the lip 45 when the valve 40 is in its rearmost position and that when said valve is pushed or pulled forwardly or to the position shown in Figure 8, said valve covers and closes the exhaust port 35.

Extending from the valve casing 37 to the front end of the valve flange receiving groove is a passageway 47 and opening from the rear portion of the piston chamber 10 into the valve chamber 38 alongside the mouth of the passageway 47 is a port 49. When the controlling valve is in its rearmost position, the port 49 is cut off from the passageway 47, but said valve 40 has a transverse channel 50, which when the valve is pushed or pulled forwardly, affords communication between the port 49 and passageway 47 (see Figures 5 and 8). More than that, the valve 40 is provided with a relief port or passageway 51 which communicates with the outer end of the passageway 47 when the valve 40 is in its rearmost position and said passageway at that time is also in communication with a port 52 formed in the outer side of the valve casing 37.

It is believed that the operation of the structure can now be made clear. When the controlling valve 40 is in its rearmost position, the cylinder exhaust port 35 is open to atmosphere. The port 49 is cut off from the passageway 47, but said passageway 47 is open to atmosphere through the passageway 51 and port 52. The apparatus then functions as already described, the passageway 47 merely acting as a relief port to permit the free movement of the flange 31 by allowing air in front of said flange to pass out of the groove 23 and return into it as the flange reciprocates. When it is desired to clean out a drill hole the operator has only to pull or push forwardly the controlling valve 40. This closes the exhaust port 35 and at the same time cuts off the passageway 47 from atmosphere, but couples it up to the rear portion of the piston chamber through the port 49 and groove 50 in the valve. The 136

result is that as the piston advances, the air under pressure behind it find its way through the passageway 47 and against the front end of the valve flange 31. This holds the valve in its rearmost position so that air under pressure is maintained in the piston chamber 10 behind the piston and the piston is therefore stopped but held firmly in its foremost position and against the tool. Air therefore under pressure will flow from the piston chamber through the chamber 13 and bore 15 in the piston to the bore of the drill steel. As soon as the valve 40 is released, it will return to its original position or as shown in Figure 2 and the drilling mechanism will again be started in normal operation.

The structure shown in Figures 6 and 7 is substantially the same as that already described, except that the spring 42 abuts a cross pin 44a on the valve stem 41. The cross pin has its ends engaged in slots 39a of the valve casing 37, and this prevents the rotation of the valve while permitting its reciprocation.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

What I claim, is:

1. In a tool of the character set forth, the combination with a cylinder member having a piston chamber, of a piston in the chamber, an automatic valve for distributing motive fluid to the piston chamber to actuate the piston, means for supplying fluid from the piston chamber to the automatic valve to hold it against automatic movement, and a reciprocatory valve for controlling the supply of holding fluid by said means to the automatic valve.

2. In a tool of the character set forth, the combination with a cylinder member having a piston chamber, of a piston in the chamber, an automatic valve for distributing motive fluid to the piston chamber to actuate the piston, means for supplying fluid from the piston chamber behind the piston to the automatic valve to hold it against automatic movement and in a position to deliver motive fluid behind the piston, and a reciprocatory valve controlling the supply of holding fluid by said means to the automatic valve.

3. In a tool of the character set forth, the combination with a cylinder member having a piston chamber, of a piston in the chamber, an automatic valve for distributing motive fluid to the piston chamber to actuate the piston, means for supplying fluid from the piston chamber behind the piston to the auto-

matic valve to hold it against automatic movement and in a position to deliver motive fluid behind the piston, said cylinder member also having an exhaust for fluid behind the piston, and a reciprocatory valve controlling the supply of holding fluid by said means to the automatic valve and also controlling the said exhaust.

4. In a tool of the character set forth, the combination with a cylinder member having a piston chamber, and a piston operating in the chamber, of an automatic valve for distributing motive fluid to the piston chamber to actuate the piston, said cylinder member having a port for exhausting fluid from the piston chamber and having a passageway leading from the piston chamber to the automatic valve for supplying fluid to the latter to hold it in a position to supply fluid to the piston chamber for drill hole cleaning purposes, and a valve movable to one position to close the exhaust port and open the passageway and to another position to close the passageway and open the exhaust.

5. In a tool of the character set forth, the combination with a cylinder member having a piston chamber and a piston operating in the chamber, of an automatic valve for distributing motive fluid to the piston chamber to actuate the piston, said cylinder member having a port for exhausting fluid from the piston chamber and having a passageway leading from the piston chamber to the automatic valve for supplying fluid to the latter to hold it in a position to supply fluid to the piston chamber for drill hole cleaning purposes, an open ended valve chamber on the cylinder member, and a valve in the chamber movable to one position to close the exhaust port and open the passageway and to another position to close the passageway and open the exhaust, said valve having actuating means at both ends of its valve casing.

6. In a tool of the character set forth, the combination with a cylinder member having a piston chamber and a piston operating in the chamber, of an automatic valve for distributing motive fluid to the piston chamber to actuate the piston, an open-ended valve chamber on one side of the cylinder member, said cylinder member having an exhaust port adjacent said chamber, a fluid supply passageway leading from the chamber to the automatic valve, a supply port opening from the cylinder member to the valve chamber, and a relief port opening from said valve chamber, and a valve in the valve chamber movable to and from a position to close the exhaust port and establish and cut off communication between the supply port or relief port and the supply passageway.

7. In a tool of the character set forth, the combination with a cylinder member having a piston chamber, of a piston in the chamber, an automatic valve for distributing motive

fluid to the piston chamber to actuate the piston, said cylinder member also having an exhaust for fluid delivered to the piston chamber, means for directing fluid from the piston chamber to the automatic valve to hold it against automatic movement, and a reciprocatory valve for controlling the supply of holding fluid by said means to the automatic valve and simultaneously closing the said exhaust.

8. In a tool of the character set forth, the combination with a cylinder member having a piston chamber, of a piston in the chamber, an automatic valve for distributing motive fluid to the piston chamber to actuate the piston and having opposing pressure surfaces, means controlled by the piston for alternately causing fluid pressure against the surfaces to automatically shift the valve, said valve having a third pressure surface, and means for causing the third pressure surface to be open to atmosphere and permit the said automatic shifting of the valve and to cause fluid under pressure to be directed against said third pressure surface to stop the valve in a position to permit the free flow of fluid into the piston chamber.

9. In a tool of the character set forth, the combination with a cylinder member having a piston chamber, of a piston in the chamber, an automatic valve for distributing motive fluid to the piston chamber to actuate the piston, and having opposing pressure surfaces, means controlled by the piston for alternately causing fluid pressure against the surfaces to automatically shift the valve, said valve having a third pressure surface, and a valve movable between a position to cause the third pressure surface to be open to atmosphere and permit the said automatic shifting of the valve and to another position to cut off said communication with the atmosphere and cause fluid under pressure to be directed against said third pressure surface to stop the valve in a position to permit the free flow of fluid into the piston chamber.

45 In testimony whereof, I affix my signature.
HJALMER C. GUSTAFSON.
